UNITED STATES PATENT OFFICE.

WENDELL L. CARLSON, OF WASHINGTON, DISTRICT OF COLUMBIA.
METHOD OF AND APPARATUS FOR RECEIVING RADIOSIGNALS.

Application filed February 14, 1922. Serial No. 536,496.

To all whom it may concern:

Be it known that I, WENDELL L. CARLSON, a citizen of the United States of America, and resident of Washington, District of Columbia, have invented certain new and useful Improvements in Methods of and Apparatus for Receiving Radiosignals, of which the following is a specification.

My invention relates generally to radio signaling, and more particularly to receiving radio signals, and has for a particular object the efficient reception of signals without employing the well-known "beat" or "heterodyne" method of reception, reference being made to U. S. Patents Nos. 1,050,441 and 1,050,728 to Fessenden, granted January 14, 1913.

One of the advantages claimed for the "beat" method of reception is that by adjusting the frequency of the local source of oscillations, the frequency of the beats may be regulated to give a note best suited to the ear of the operator. This same advantage has been obtained without employing the "beat" method, reference being made to U. S. Patent 1,170,552 to Meissner, granted February 8, 1916. By adjusting the local source of low frequency oscillations of Meissner, a change can be made in the note in the receiver so as to be suitable to the ear of the operator.

There are certain disadvantages in the method proposed by Meissner and it is the purpose of my invention to render more effective this mode of reception. For instance, it will be readily obvious that to receive weak signals the local signals must be entirely eliminated at the ear of the operator when no signals are coming in, otherwise, it will be difficult to recognize the real signals when they come through. Meissner endeavors to accomplish this by loose coupling and tuning, but it is doubtful if the local signals can be entirely eliminated in this way, and it is certain that these expedients will greatly reduce or even eliminate the desired signal when the arrangement is actuated by a weak incoming signal.

The manner in which I have improved this method of receiving signals will best be understood by reference to the drawing. V is an ordinary 3-electrode vacuum tube having heated filament F, plate P and grid G. The grid-filament circuit of this tube is excited through transformer T by a local source of audible oscillations, which source

may be a buzzer, tuning fork buzzer, vacuum tube oscillator or other suitable generator, and the extent of excitation may be regulated at the generator itself or the amount of coupling in transformer T. The plate-filament circuit is excited by the incoming signals received on antenna A, the strength of such excitation being boosted if necessary by a series of 3-electrode vacuum tube amplifiers A₁, A₂, A₃, and A₄ and their circuits, or other suitable feeble electric current amplifiers. A₄ is also a 3-electrode vacuum tube amplifier which may be inserted after the tube V to intensify the final signal in telephones P or other suitable responsive device. L₁ and L₂ are lines supplying electrical energy for heating the filaments of all of the vacuum tubes, the amount of such energy being controlled by ballast lamps B₁, B₂, B₃, B₄ and B₅, as well as at the source, except in the tube V where rheostat R and contact C₁ allow a special control. P₁ and P₂ are potentiometers across lines L₁ and L₂ which permit of securing a negative bias on the grids of the amplifiers. These ballast lamps and potentiometers are ordinary means of control, but others well known to the art may be used. Lines L₂ and L₃ supply energy for exciting the plate-filament circuits of the amplifiers, it being general to control the potential on these circuits at the source. It will be noted that tube V is not excited from this source. Contact C₂ on the rheostat R permits of securing an adjustable negative bias on the plate P of tube V.

Operation is as follows: The tube V has its grid-filament circuit excited by the energy of the local oscillations, but no effect is had in the telephones P because the plate-filament circuit of the tube is dead; that is, there is no potential difference between the plate P and the filament F to cause a current flow in the tube. Or should there be a slight flow from whatever cause, this can be eliminated by giving the plate P a slight negative bias through contact C₂ or by adjusting the temperature of the filament F through contact C₁, or by proper adjustment of both. Having adjusted so that there is no sound in the telephones P, when a signal is received on the antenna A, it excites the plate-filament circuit of the tube V, rendering the plate P alternately positive and negative at a frequency in keeping with that of the incoming signal. Every time the plate P is made positive a current flows in

the tube, and therefore in the plate-filament circuit. These high frequency uni-directional current pulses are modulated by the local oscillations exciting the grid G at an audible rate with the result that the incoming signal manifests itself in telephones P through a note in accordance with the local oscillations. It is obvious that this note can be regulated by the operator to suit his own peculiarities if he is provided with a local generator variable in frequency.

Having fully described my invention, what I desire to secure by Letters Patent is:—

- 15 1. The method of receiving and translating into a signal radio frequency signal-representing energy, which comprises receiving the signal-representing energy, and rectifying the current thereof in a circuit whose impedance is always finite, independently generating an electromotive force varying in amplitude at predetermined frequency, producing variations of impedance of said circuit by said electromotive force only when said signal-representing energy is being received and translating into a signal the rectified current as modified by said impedance variation.
- 20 2. In a receiver of high frequency electrical oscillations, a three-electrode vacuum tube, means for exciting the grid-filament circuit of said tube with locally generated oscillations, means for negatively biasing the plate of said tube, means for exciting the plate-filament circuit of said tube with the high frequency oscillations, and means

for observing the resultant current flow in said plate-filament circuit.

3. In a receiver of high frequency electrical oscillations, a three-electrode vacuum tube, means for exciting the grid-filament circuit of said tube with locally generated oscillations, means for adjusting the condition of the electrodes of said tube to prevent a current flow in its plate-filament circuit, due to said local excitation, means for exciting said plate-filament circuit with the high frequency oscillations so as to disturb said adjusted condition of the electrodes of said tube, and means for observing the resultant current flow in the plate-filament circuit.

4. In a radio receiving system, a plurality of coupled amplifying tubes, one of said tubes having its plate-filament circuit interposed in its coupling with the preceding tube, a local source of audible oscillations interposed in the grid-filament circuit of the last-named tube, and a negative bias for the plate of said tube.

5. The method of receiving and translating into signals radio frequency signal representing currents, which comprises rectifying the radio signal currents in a circuit in which no current can normally flow, producing variations of impedance in said circuit only when signal energy is being received, and then translating into a signal the rectified current as modified by said impedance variations.

WENDELL L. CARLSON.
